[57] **CLAIM**

The ornamental design for a tire tread, as shown and
described.

DESCRIPTION

FIG. 1 is a perspective view of a tire tread, it being
understood that the tread pattern repeats uniformly through-
out the circumference of the tire;

FIG. 2 is a front elevational view thereof;

FIG. 3 is a side elevational view thereof; and,

FIG. 4 is an enlarged fragmentary front view thereof.

The broken line showing of the tire sidewall in the drawings
is for illustrative purposes only and forms no part of the
claimed design.
